Application April 16, 1938, Serial No. 202,414

9 Claims. (Cl. 229—5.5)

This invention relates to containers, and with regard to certain more specific features, to paper containers and their manufacture.

Among the several objects of the invention may be noted the provision of strong paper containers which partake of the economy and lightness of cardboard containers and also of the greater strength of wood, fibre and metal containers or the like; and the provision of containers of the class described which may be manufactured in various sizes on a production basis with the necessary accuracy. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated several of various possible embodiments of the invention,

Fig. 1 is a perspective view showing the first step in making a relatively long inner drum;

Fig. 2 is a perspective view illustrating a step used in making a shorter outer drum;

Fig. 3 is a perspective view showing a step in making a cover;

Fig. 4 is a longitudinal section, diagrammatically illustrating the assembly of the products of the steps of Figs. 1 and 2;

Fig. 5 is an enlarged detail section of the container wall after completion;

Fig. 6 is an enlarged fragmentary sectional detail of a bottom corner of a finished container;

Fig. 7 is a view similar to Fig. 6 but showing a top corner of the cover;

Fig. 8 is a side elevation, partly in section, diagrammatically illustrating the finished and closed container;

Fig. 9 is a view similar to Fig. 8, but showing an alternative form of the invention, the cover being removed;

Fig. 10 is a perspective view similar to Fig. 1 showing a step in the process of making the body of the article of Fig. 9;

Fig. 11 is a perspective view showing a step in the process of making the cover for the article of Fig. 9;

Fig. 12 is a view similar to Fig. 1 showing an alternative form of the invention; and,

Fig. 13 is a view similar to Fig. 1 showing still another alternative form of the invention.

Similar reference characters indicate corre-

sponding parts throughout the several views of the drawings.

The drawings are necessarily exaggerated as to the thickness of material used, and therefore bulk in certain regions is exaggerated and appears to be greater than it is in practice. This exaggeration also causes voids to appear where, in fact, there are none, or where they are so small as to be negligible from the viewpoint of strength and durability of the container.

In its referred form, the entire container is made of relatively thin and flexible paper. By way of example, and not limitation, kraft paper may be used of a thickness of 16 points (.016").

Such paper ordinarily comes in rolls of predetermined widths and may therefore be handled most conveniently in manufacture as a long continuous strip. Such a strip is shown, for example, at numeral 1 in Fig. 1. The width of strip 1 is the greatest of any of the strips used in the process, inasmuch as this strip is to form an inner cylinder which substantially predetermines the length of the finished container ignoring certain head thicknesses.

While various modifications may be made in the mode of manufacture of our container, depending upon whether it is made by machine, or partly by hand and partly by machine, we have chosen first to illustrate and described the form shown in Figs. 1-3, because this form admits of the most direct and lucid description. After the description of this form of Figs. 1-3, other forms will be described.

Referring to Fig. 1, the first operation to be performed on strip 1, as well as upon all of the other strips hereinafter described in connection with Fig. 1, is to notch one edge as at 3, the other edge 5 being left straight. The notches 3 are of triangular shape and let triangular tabs 7 remain. When these tabs 7 are turned over, as will be described, their adjacent edges are substantially spaced from one another, so that the overlap or staggering that occurs between successive layers of tabs will result in a thinner but stronger construction in which voids are reduced.

The strip 1 is convolutely wound on itself upon a cylindric and rotary mandrel 9 to form a body member of a predetermined number of plies. As successive windings of the strip 1 are applied, an adhesive such as glue is applied between windings, as indicated by stippling. However, the first loop or winding on the mandrel is left free of adhesive so that it does not stick to the mandrel, but may be subsequently slipped off.

The arrangement of the strip 1 with respect to

the end 11 of the mandrel 9 is such that the tabs 7 extend axially from the edge of the mandrel 9 with the bottoms of the notches 3 spaced a short distance from the end of the mandrel. Hence, considering the succession of windings as plies, the tabs project integrally from and throughout the peripheral edge of each ply, and form on each ply a peripheral series or circuit of tabs.

Fig. 1 indicates that a single winding or lamination of paper with a single circuit of tabs has been applied to the mandrel 9. At this stage, a disc 13 of a predetermined number of circular paper bottom discs 13, 13a, 13b, 13c and 13d, which number corresponds generally to the number of the windings or plies making up the body thereof, (see also Fig. 6) is positioned against the end 11 of the mandrel, and within the confines of the extending tabs 7, adhesive having theretofore been applied to the outer surface of the disc 13, as indicated by the stippling. The circuit of tabs 7 around the edge of the disc 13 is then turned or folded down over the edge of disc 13. The thickness of each disc 13, 13a, 13b, 13c and 13d is of the order of that of the strip 1, and it is preferably not of a thickness to be 25 characterized as cardboard.

With the first disc 13 applied and the first circle of tabs 7 turned down to hold the disc, the mandrel 9 is rotated more to roll up another loop of the strip 1, that loop adhering to the one under it. This results in another circular group of tabs 7 being axially located at the edge of the surface 11, this group now extending outwardly from the first paper disc 13.

Next, the second paper disc 13a is moved endwise to cover the folded tabs 7 and to become adhered to the outside of the first-applied paper disc 13. Adhesive is placed either on the front of the disc 13a (as shown), or over the bent tabs 7 to assure a strong bond between the discs 13, 13a and the tabs. Next, the second group of tabs 7 is turned down to be held in position by the adhesive on them to the back of disc 13a. Thus, the effect of the application of the second disc 13a is to sandwich the first group of tabs 7 which were turned down on disc 13 and to increase the thickness and strength of the head thus being formed. The second row of tabs 7 holds this second head 13a in place.

The process is continued until, say, five loops of paper from strip 1 have been convolutely wound around the mandrel 9 and adhered to one another, with five applied discs 13, 13a, 13b, 13c, 13d, the discs interleaving with the tabs 7. This forms a tubular shell. It should be understood that, although the first disc 13 has adhesive on its outside, the discs 13b, 13c and 13d have adhesive on their insides (side toward the mandrel 9). As above made clear, the disc 13a also may have adhesive on the inside (so as to cover the adhesive-free outsides of the first row of tabs 7), or this second disc 13a may be entirely free of adhesive and depend upon the adhesive on the first disc 13, provided that adhesive has been provided on the outside of the first row of tabs 7 after these tabs have been turned down.

The strip 1 is then cut off, ready for the manufacture of the next tubular shell, and the finished shell is removed from the mandrel 9. This forms the inner tubular shell of the container, which will be designated generically by the index N, and which is shown diagrammatically in Figs. 4 and 8. This shell N comes from the mandrel 9 in a wet condition, due to the fluidity of the glue which is used between the layers forming both 75

the cylinder 17 and the enclosing head 19. This inner shell N is then aged, that is, dried, so that it shrinks to a stable condition.

In Fig. 2 is illustrated how a second and outer shell O is likewise formed. This shell is formed from a strip 21 which is narrower than the strip 9 by the length L indicated in Fig. 8, thus providing a length of outer cylinder O which is likewise shorter than the cylinder N by this length L. The length L is the amount of projection of the inner cylinder N desired for telescoping within the cover C.

As indicated in Fig. 2, the strip 21 also has notches 3 forming tabs 7. The strip 21 is so related to a mandrel 23 that the circuit of tabs around the mandrel end 25 extends axially as in the case of Fig. 1. Windings, application of adhesive, and successive applications of paper heads 27 et seq. with bending over of the tabs 7 follow the method described in connection with Fig. 1. Thus, the shorter outer cylinder O is formed like the longer inner cylinder N. Its inside diameter while wet is caused to be slightly larger than the outside diameter of the inner cylinder N while dry.

In the present example, the outer cylinder O is shown also as being made up of five convolute loops of the strip 21 with five heads, such as shown at 27, 27a, 27b, 27c and 27d (Fig. 6). The five heads, 13, 13a, 13b, 13c, and 13d, are smaller than the five heads 27, 27a, 27b, 27c and 27d, because they are associated with the smaller cylinder N. A final, large paper head 29 is used to make a final covering for the end of cylinder O and the last row of tabs 7 which is turned down. Thus, a neat outer appearance is presented. It will be understood that, if desired, the five heads 27 et al. may be made the same size as the five heads 13 et al., the tabs 7 making up the difference radially. Such a construction would avoid the necessity for using two different sizes of heads.

Before the outer cylinder O has cured, or dried, that is, while it is still in a pliable and extended condition, the now cured inner cylinder N is slipped therein, after application of adhesive within the outer cylinder O, as indicated by the stippling in Fig. 4. The application of adhesive to the inside of the cylinder O may be over its entire inner surface or over a less, but sufficient, area to effect the desired end of strong adherence. Fig. 4 shows the application of the inner cylinder to the outer cylinder, before complete assembly. Adhesive may also be placed between the bottoms 19 and 31.

It is also contemplated that adhesive may be eliminated between bottoms 19 and 31, in which event the advantages are had of relative motion between the bottoms 19 and 31 during deformation and the cushioning effect of a slight amount of air therebetween. This possibility of relative movement (not unlike the leaves of a spring) between bottoms 19 and 31 and the interposition of the resulting small air pocket for some materials provides a stronger container.

Next, the outer shell O dries and shrinks onto the inner cylinder N, with the result that any side wall section, such as shown in Fig. 5, has as homogeneous a character as if the strip 21 had been wound around strip 1. Thus, it will be seen that there is obtained a unitary cylindric container, so far as strength is concerned, having an inwardly shouldered off-set at its upper end for telescopic reception of the cover C. It should here be made clear that all layers of adhesive

used are extremely thin, and that the adhesive tends to penetrate paper and to form a keyed bond as indicated in Fig. 5.

A flatter bottom wall can be obtained by placing each shell N and O, while moist from adhesive, on a flat surface and pressing down the bottoms 19 and 31 by suitable plungers. A similar pressure operation may also be performed after the two shells have been assembled and the bottoms 19 and 31 combined, or this operation may be used exclusively.

Fig. 6 illustrates another feature, which is the fact that the ends of all of the tabs become arranged along a diagonal 15, in every cross-section, thus tending to make the transition, from the increased number of layers near the cylinder wall to the smaller number of layers at the center of the head, more gradual, with a neater appearing result. The triangular forms of the tabs 7, with the inevitable overlapping in successive layers, enhances the effect of gradual transition. It should be understood that Fig. 6 is idealized, and that actually successive tiers of the tabs 7 may be staggered peripherally.

An advantageous feature of the invention is that the cured shell N, being smaller than the uncured shell O, may be slipped therein with great ease, and thereafter the uncured shell O cures and shrinks into an irremovable condition on the outside of the inner shell N. By this method, a very strong and permanent laminated container shell is effected, having the form desired.

The procedure for forming the cover C is to convolutely wrap a still narrower paper strip 33, as shown in Fig. 3, on a third mandrel 35, said strip 33 having notches 3 providing tabs 7 which also extend axially from the end surface 37 of mandrel 35. Successive convolute loops of the strip 33 with interspaced adhesive are used in connection with successively applied paper discs 39, 39a, 39b, 39c, and 39d, the successive circles of tabs 7 being bent over and sandwiched by the discs (see also Fig. 7). Finally, a larger cover disc 41 is used for providing a neat appearance.

For equal strength the end of cover C should have a thickness which is about that of the combined ends 19 and 31 of the assembled shells N and O. Hence, a series of discs 43 are applied internally, interspersed with adhesive to form a strong laminated structure of desired thickness.

After the cover C has been completed, it is allowed to cure, or dry, before being telescoped over the reduced end 45 of the combined shell N, O. When it is telescoped the relationship shown in Fig. 8 exists. For final closure after loading, the adhesive tape 2 is used.

By way of example, the outside diameter of the mandrel 23 in Fig. 2 is made about equal to the outside diameter of shell N when the latter is wet. This produces an outside shell O which will readily receive the inside shell N when the latter is dry, and upon shrinking will form a homogeneous structure such as shown in Fig. 5. Variations in dimensions are permissible within limits adapted to produce the desired effect.

The outside diameter of the mandrel 35 is made about equal to the diameter of mandrel 23, or a little larger or smaller, depending upon the snugness of the telescoping fit desired between the inside of the cover C and the reduced end of the assembled shell N, O. No adhesive is placed on the inside of the cover C upon closure, so that the container may readily be reopened.

If desired, the wet end 47 of the cover C may also be pressed against a flat surface by a piston or plug, as described in connection with the ends 19 and 31, so that the laminations may be squeezed into a flatter condition, that is, the ends of the tabs in successive circuits or layers are at different distances from the center line of the container.

As shown in Fig. 7, the ends of the tabs 7 in the cover C also arranged themselves along a diagonal. Many advantages can be obtained by proceeding as above described in connection with the mandrel 9 and the wide strip 1, and thereafter adding the narrow strip 21 by winding it directly onto the wound strip 1 on the mandrel 9, thus producing a homogeneous wall, without the two-cylinder constructions above outlined.

An alternative form of the invention is shown in Fig. 9, wherein a preformed inner cylinder 51 is used, and this may be a wrapped convolute construction without the tabs, or similar construction suitable for the purpose. At the lower end of this cylinder 51 is a preformed disc 53 made of similar material, and preferably of a diameter equal to the outside diameter of the cylinder 51.

As shown in Fig. 10, the cylinder 51 is slipped over a mandrel 55, and the disc 53 is placed against the end of it and a plain strip of paper 57 is then wound so as to attach itself both to the cylinder 51 and to the disc 53, adhesive being used for the purpose.

The strip 57 has no tabs, as in the form of the invention shown in Figs. 1-8, but has an edge lying flush with the outer surface of the disc 53.

Discs 59 are provided with radial tabs 61. These are provided with adhesive on the side adjacent the disc 53 and attached to said disc, the tabs 61 being turned into axial position to adhere axially against the wound strip 57. Then, a successive convolute turn of the strip 57 is applied around the tabs 61, and a second disc 59a is applied, the strip 57 being led out from behind the applied circle of tabs by its edge passing through a space between two tabs 61. This process is continued until the desired number of laminations is obtained.

As shown in Fig. 11, a disc 63 is placed against the end of a mandrel 65 of equal diameter, and a strip of paper 67 applied to provide one revolution, the one edge of the paper fastening itself to the edge of the disc 63 by suitably applied adhesive. The successive discs 69, 69a, etc., are applied in the manner above described in connection with Fig. 10, so that the successive circuits of radial tabs 61 are interwoven with successive loops of the strip 67. The finished effect is illustrated in Fig. 9.

It should be understood that the cylinder 51 may itself be formed by winding on the mandrel, and the loops which compose it when thus made, may carry tabs which sandwich between separate discs which may be made to compose the disc 53. In other words, a construction such as is illustrated in the making in Fig. 1 may be combined with the outer construction shown in Fig. 9, wherein the discs carry the tabs. The drawings have not been complicated by a showing of such a combined construction, because it is believed to be an extension of the invention which is clear from this description.

One of the advantages of the invention is the closely knit structure obtained by using a comparatively larger number of thin laminations, both in the container wall, and in its ends, these

laminations of the respective parts being interleaved by means of the staggered tabs at a large number of points, so that whatever loads are applied due to mishandling of filled containers are resisted with a relatively low stress over the relatively large adhering areas involved. The container, furthermore, presents a neat appearance.

It will be understood that, although paper is shown as that which composes the various laminations of the container described, other material may be used which is of paper thickness for winding the successive cylindric laminations for providing head discs and tabs. For example, cloth may be used.

An important feature of the invention is the fact that the laminations are thin (of paper thickness), so that a large number are used in a given thickness, with the result that, when a substantially rigid condition is reached (by multiplication of laminae), a stronger container is obtained.

In Fig. 12 is shown a form of the invention showing alternative details adapting it particularly for machine manufacture. Fig. 12 shows 25 the steps that correspond only to the steps of Fig. 1. The successive steps corresponding to the steps shown in Figs. 2 and 3 have not been shown, because they will be obvious from the following description. In Fig. 12 like numerals 30 designate like parts.

The procedure shown in Fig. 12 is to leave bare of adhesive the first convolute loop of the material to go around the mandrel 9, with the exception of adhesive which is applied only to the extending first loop of tabs 7. It is then possible to leave all adhesive off of the first bottom disc 11. Then, when the tabs are bent over, the adhesive thereon causes them to stick to the outside of the disc 11, to hold it.

On the successive convolute loops of material 1, adhesive is applied all the way across, including the tabs, as indicated by the stippling in Fig. 12. Then disc 11a is applied within the second loop of tabs, and these tabs are turned over said disc 11a. The disc 11a has adhesive on its inside (mandrel side), and thus holds to the outside of disc 11 and the outside of the tabs 7 which have been turned over said disc 11. The remainder of the construction is carried out by repeating the operations on successive discs, such as 11a.

The advantage of the procedure illustrated by Fig. 12 is that the outside of all discs 11, 11a, etc., may be engaged by automatic suction holding apparatus for application to the end of the mandrel.

In Fig. 13 is shown a procedure which corresponds to that shown in Fig. 1, except that the adhesive which is applied to the strip is applied to the outside rather than to the inside. Like numerals designate like parts. It will be understood that, in Figs. 1-3 and 10-12, it is possible to use a dry calendering roll against the mandrel 9 after paper is rolled onto the mandrel. This is because the outside of the paper is dry. The calendering roll is not shown in the drawings, because the use of such rolls is known practice. In the case of Fig. 13, adhesive may be applied by a glue roll pressing against the mandrel 9 at or to the rear of the point where the paper is fed on, the glue roll also acting as a calendering roll if desired. The procedure otherwise is the same as in Fig. 1. The purpose of Fig. 13 is primarily to illustrate the fact that the same 75

structural result, so far as the container is concerned, is obtained by applying the adhesive on either side of the paper being wrapped onto the mandrel 9.

It is to be understood that the containers above described are designed to carry weights up to several hundred pounds, and that they are designed to be used as shipping containers. The construction is such that they equal or exceed the requirements of regulations for similar containers specified in the Consolidated Freight Classifications and in the regulations of the Interstate Commerce Commission covering dangerous articles, such as explosives.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

We claim:

1. A container comprising a multi-ply body member and a multi-ply end member closing one end of the body member, the body member being formed of a continuous strip of material of paper thickness wound on itself and forming a wall of a predetermined number of plies, said end member being formed of plies of material of paper thickness and which correspond in number to the number of plies of the body member, integral tabs projecting from and throughout the peripheral edge of each ply of one of said members thereby to form on each said ply a peripheral series of tabs, each series of tabs projecting between corresponding plies of the other member, and said tabs and plies being adhesively secured throughout.

2. A container comprising a multi-ply body member and a multi-ply end member closing one end of the body member, the body member being formed of a continuous strip of material of paper thickness wound on itself and forming a wall of a predetermined number of plies, said end member being formed of plies of material of paper thickness and which correspond in number to the number of plies of the body member, integral tabs projecting from and throughout the peripheral edge of each ply of one of said members thereby to form on each said ply a peripheral series of tabs, each series of tabs projecting between corresponding plies of the other member, the tabs of each series thereof being more or less staggered with relation to the tabs of adjacent series thereby to provide a relatively thin joint between the body and end members, and said tabs and plies being adhesively secured throughout.

3. A container comprising a multi-ply body member and a multi-ply end member closing one end of the body member, the body member being formed of a continuous strip of material of paper thickness wound on itself and forming a wall of a predetermined number of plies, said end member being formed of plies of material of paper thickness and which correspond in number to the number of plies of the body member, integral tabs projecting from and throughout the peripheral edge of each ply of one of said members thereby to form on each said ply a peripheral series of tabs, each series of tabs projecting between corresponding plies of the other member,

the tabs of each series thereof being more or less staggered with relation to the tabs of adjacent series, the ends of the tabs of each series thereof in relation to the ends of the tabs of adjacent series being differently spaced from the center of said end member, and said tabs and plies being adhesively secured throughout.

4. A container comprising a cylindrical multi-ply body member and a circular multi-ply member closing one end of the body member, the body member being formed of a continuous strip of material of paper thickness wound on itself and forming a wall of a predetermined number of plies, said end member being formed of plies of material of paper thickness and which correspond in number to the number of plies of the body member, integral tabs projecting from and throughout the peripheral edge of each ply of the body member, thereby to form on each said ply edge a peripheral series of tabs, each series of tabs projecting between corresponding plies of the end member, and said tabs and plies being adhesively secured throughout.

5. A container comprising a cylindrical multi-ply body member and a circular multi-ply member closing one end of the body member, the body member being formed of a continuous strip of material of paper thickness wound on itself and forming a wall of a predetermined number of plies, said end member being formed of plies of material of paper thickness and which correspond in number to the number of plies of the body member, integral tabs projecting from and throughout the peripheral edge of each ply of the body member, thereby to form on each said ply edge a peripheral series of tabs, each series of tabs projecting between corresponding plies of the end member, the tabs of each series thereof being more or less staggered with relation to the tabs of adjacent series thereby to provide a relatively thin joint between the body and end members, and said tabs and plies being adhesively secured throughout.

6. A container comprising a cylindrical multi-ply body member and a circular multi-ply member closing one end of the body member, the body member being formed of a continuous strip of material of paper thickness wound on itself and forming a wall of a predetermined number of plies, said end member being formed of plies of material of paper thickness and which correspond in number to the number of plies of the body member, integral tabs projecting from and throughout the peripheral edge of each ply of the body member, thereby to form on each said ply edge a peripheral series of tabs, each series of tabs projecting between corresponding plies of the end member, the tabs of each series thereof being more or less staggered with relation to the tabs of adjacent series, the ends of the tabs of each series thereof in relation to the ends of the tabs of adjacent series being differently spaced from the center of said end member, and said

tabs and plies being adhesively secured throughout.

7. A container comprising a cylindrical multi-ply body member and a circular multi-ply end member closing one end of the body member, the body member being formed of a continuous strip of material of paper thickness wound on itself and forming a wall of a predetermined number of plies, said end member being formed of plies of material of paper thickness and which correspond in number to the number of plies of the body member, integral tabs projecting from and throughout the peripheral edge of each ply of said end member thereby to form on each said ply a peripheral series of tabs, each series of tabs projecting between corresponding plies of the body member, and said tabs and plies being adhesively secured throughout.

8. A container comprising a cylindrical multi-ply body member and a circular multi-ply end member closing one end of the body member, the body member being formed of a continuous strip of material of paper thickness wound on itself and forming a wall of a predetermined number of plies, said end member being formed of plies of material of paper thickness and which correspond in number to the number of plies of the body member, integral tabs projecting from and throughout the peripheral edge of each ply of said end member thereby to form on each said ply a peripheral series of tabs, each series of tabs projecting between corresponding plies of the body member, the tabs of each series thereof being more or less staggered with relation to the tabs of adjacent series thereby to provide a relatively thin joint between the body and end members, and said tabs and plies being adhesively secured throughout.

9. A container comprising a cylindrical multi-ply body member and a circular multi-ply end member closing one end of the body member, the body member being formed of a continuous strip of material of paper thickness wound on itself and forming a wall of a predetermined number of plies, said end member being formed of plies of material of paper thickness and which correspond in number to the number of plies of the body member, integral tabs projecting from and throughout the peripheral edge of each ply of said end member thereby to form on each said ply a peripheral series of tabs, each series of tabs projecting between corresponding plies of the body member, the tabs of each series thereof being more or less staggered with relation to the tabs of adjacent series, the ends of the tabs of each series thereof in relation to the ends of the tabs of adjacent series being differently spaced from the center of the end member, and said tabs and plies being adhesively secured throughout.

LESTER B. LEIGHTON,
CLARENCE J. VOGT.
